United States Patent Office.

A. FROST, OF SEYMOUR, INDIANA.

Letters Patent No. 80,938, dated August 11, 1868.

IMPROVED APPLE-CORER AND CUTTER.

The Schedule referred to in these Letters Patent and making part of the same.

TO ALL WHOM IT MAY CONCERN:

Be it known that I, A. FROST, of Seymour, in the county of Jackson, and State of Indiana, have invented certain new and useful Improvements in Machines for Cutting and Coring Apples; and I do hereby declare that the following is a full, clear, and exact description thereof, reference being had to the accompanying drawings, and to the letters of reference marked thereon, which form a part of this specification, in which—

Figure 1 is a perspective view, and

Figure 2 is a bottom view of the slides, showing the operation thereof.

The nature of my invention consists in the construction of a simple and cheap device for coring and cutting apples, which can be operated by any child, almost, if desired.

In order to enable others skilled in the art to make and use my invention, I will now proceed to describe its construction and operation.

A represents a bed-piece, which is grooved out in its centre, to allow the sliding bars, B and C, to move back and forth.

On the left end of the bed-piece A is a vertical piece, D, fastened, which extends a suitable distance to the rear, and is cut with a circular hole opposite the centre of the bed-piece. This hole is provided with four knives, a a, which radiate at right angles from each other from a tube, b, which passes through the centre of this hole, being secured in the rear of the board D to an angular bar, E, which is fastened to said board.

On the sliding bar B is an upright rod, c, to which is an annular disk, F, secured, the centre hole or opening of the said disk being about the size of the core of an apple. On the sliding bar C is a similar upright rod, d, to which is secured a head, G, pointing directly against the end of the tube b, and to this head four knives, e e, are secured.

These knives are made of any suitable material, and are provided at their front ends with projections and slots running into each other, as shown, and are further made to give, that is, separate, as far as may be necessary, to completely core the apple.

A lever, H, is connected to the rear end of the board D, by means of a hook, f, and extends forward, under the head G, to the left of the rod d, and is pivoted on a pin, i, on the slide B, to the right of the rod c, extending far enough in front of the bed-piece A to be operated from that side.

The operation is as follows:

Place the apple on the end of the tube b, then move the lever H towards the board D; this moves the slide B, and also the slide C, by means of a catch, m, placed on the bottom of said slide C, which catches into a notch on the slide B, as shown in fig. 2.

This moves the knives e e into the apple, completely cutting out the core of the same, and, as soon as the knives strike the end of the tube b, a notch in the groove of the bed-piece A throws the catch m out from the notch in the slide B, allowing said slide to keep on towards the apple. The annular disk F then presses the apple against the knives a a, cutting it in four parts, the pieces dropping down on the outer side of the board D, in a vessel placed for their reception.

The lever H is then moved back, carrying the slide B along with it, until the lever strikes the rod d; when the slide C also moves back to its original position, the catch m at the same time pressing in the notch on the slide B, ready for its next forward movement.

Having thus fully described my invention, what I claim as new, and desire to secure by Letters Patent, is—

1. The slide C, provided with rod d, head G, and knives e e, in combination with the tube b, in the centre of the circular hole on the board D, all constructed substantially as described, for the purpose of cutting the core out of apples, as herein set forth.

2. The combination and arrangement of the grooved bed-piece A, board D, lever H, slides B and C, knives a a and e e, and annular disk F, all constructed as described, and operating substantially as and for the purposes herein set forth.

In testimony that I claim the foregoing as my own, I affix my signature in presence of two witnesses.

A. FROST.
